UNITED STATES PATENT OFFICE.

MELVIN H. SIDEBOOTHAM, OF NASHUA, NEW HAMPSHIRE, ASSIGNOR TO ELIE W. LABOMBARDE, OF NASHUA, NEW HAMPSHIRE.

TABBING-MACHINE.

1,274,093.

Specification of Letters Patent. Patented July 30, 1918.

Application filed August 17, 1917. Serial No. 186,705.

To all whom it may concern:

Be it known that I, MELVIN H. SIDEBOOTHAM, a citizen of the United States, resident of Nashua, in the county of Hillsboro and 5 State of New Hampshire, have invented certain new and useful Improvements in Tabbing-Machines, of which the following is a specification.

This invention relates to the manufacture 10 of paper box members having reinforced corners, and the object of said invention is to provide a machine which will rapidly and automatically affix reinforcements, such as sections of strong gummed paper, to those 15 portions of the blanks which form the corners of the boxes or box covers after the blanks are folded.

To this end, the invention consists in the construction and combination of parts 20 substantially as hereinafter described and claimed.

Of the accompanying drawing:—

Figures 1 and 2, are respectively a sectional elevation and a plan view of so much 25 of the machine as is necessary to illustrate the invention, Fig. 1 being drawn on line 1—1 of Fig. 2.

Fig. 3 is an elevation of one of the rotating disks carrying the strip affixing mechanism on a larger scale than in Fig. 1.

Fig. 4 represents a section on line 4—4 of Fig. 3 on a larger scale.

Fig. 5 represents a section on line 5—5 of Fig. 3 on a larger scale.

Fig. 6 is a broken out plan view of a box blank which has had reinforcements applied thereto by the machine.

Similar reference characters designate similar parts in all of the views.

Portions of the frame of the machine, connected by suitable braces or tie rods, are shown at 12. By suitable feeding mechanism, not necessary to illustrate, the flat blanks are fed, one at a time and properly spaced, between upper and lower carrying belts 13, 14. Said blanks may be of any of the types to which reinforcing strips or tabs are to be affixed. One form is shown at *a* in Fig. 6, the reinforcements or tabs being indicated at *b*. When this kind of blank is afterward folded to make the receptacle or cover member of the box, the sections *c*, *f*, are folded onto sections *d*, *e*, and adhesively connected, thus forming double-thick walls. Then the portions *e*, *f*, at each end, with the

tabs *b* inclosed thereby, turned toward each other and the sections *g*, *h*, are folded over said portions *e*, *f*, and secured. This forms a box member all the walls of which are of double thickness, with concealed tabs or reinforcements at the four corners where the greatest rupturing strain is liable to occur. The present machine does none of this folding, but cuts off sections of tabbing material *b* from sources of supply, and affixes four 60 of them to the proper portions of each blank, said machine having no reciprocating members, all parts operating by continuous motions and therefore enabling a high speed of production to be obtained.

At the delivery end, the upper belt 13 is mounted on a pulley 15 (Fig. 2) carried by shaft 16, and the lower belt 14 is mounted on a pulley 17 carried by shaft 18.

To insure accuracy of spacing of the 75 blanks, or the timing of their travel past the devices presently described, an endless chain 19 having properly spaced pins 20, is mounted on sprockets 21, 22, carried by shafts 16 and 23 respectively. In practice the belts 13, 80 14, do not grip the blanks very tightly, and they are driven a little faster than the chain, so that each blank is carried forward by the belts until its front edge abuts a pin 20 after which the belts slip a little over the surface of the blank but keep it in contact with said pin, so that accurate locations or portions of the blank will be moistened and receive the tabs or reinforcements as presently described.

The operative stretch of chain 19 runs along side of and parallel with a sufficient length of the operative stretch of belt 13 to secure the result just described, it being understood, of course, that suitable guides (not necessary to illustrate) for the edges of the blanks are employed to keep the blanks from traveling askew.

To moisten those areas of the blanks which are to be reinforced, a shaft 24 is 100 provided with two pairs of arms 25, 26, each having an absorbent pad 27, said pads being adapted, as they rotate, to dip into a water tank 28, and then moisten the portions of each blank where the tabs *b* are to 105 be applied. The hubs of the arms 25, 26 are independently adjustable on shaft 24, by any well known means. Lateral adjustment provides for different widths of blanks, and rotative adjustment provides for different 110

lengths of blanks. When properly adjusted, the four pads will moisten areas of the blanks, near their corners, slightly exceeding the sections of tabbing material *b* to be applied as indicated in Fig. 6. To oppose upward pressure of the pads, as they rotate, or, in other words, hold the blanks so that the pads will press with sufficient force to insure proper moistening, suitable idle 10 rolls 29 (Fig. 1) are employed.

The four devices for cutting off proper lengths of gummed reinforcing material *b* and affixing them to the four moistened areas of each blank in transit will now be 15 described. As said devices are alike, a description of one will suffice. Each comprises a disk 30 carrying strip feeding and cutting mechanism as presently described. The four disks are carried by two shafts 31, 20 having their bearings in brackets or frame uprights 32, said shafts having gears 33, both of which mesh with an intermediate gear 34 driven by a pinion 35 carried by a drive shaft 36, whereby both shafts 31 and 25 the four disks are rotated in the same direction as indicated in Figs. 1 and 3 by the arrows. Each bracket 32 supports a fixed stud pin 37, on which are adjustably mounted two arms 38, 39, the extreme ends of 30 which are inclined or beveled to act as cams as hereinafter described. As shown in Fig. 2, each cam arm 38 is set a little farther away from its associated disk 30 than its companion cam arm 39 for a reason to be 35 described.

As best shown in Fig. 3, a coil of the reinforcing material *b* is mounted upon the hub of disk 30, said material being paper or a strip of cloth or other suitable material, 40 having a coating of adhesive on its outer surface. The strip passes over a roll 40 mounted on a stud pin projecting from the side of the disk, then through a guide 41, between a feed roll 42 and a pressure roll 43, 45 through a guide 44, and then between knife members 45, 46, all carried by the disk. The guides are laterally curved or arched (see Fig. 5) to cause the strip, as it issues under the fixed cutter 45, to project stiffly in a radial direction and not be deflected or bent 50 backward by the resistance of the atmosphere, or turn sidewise, when the disk is revolving rapidly in the direction of the arrow.

55 The feed roll 42 is actuated intermittently and alternately with the cutter 46. Said feed roll is mounted on a pin 47 (Fig. 4) carried by disk 30 and has a ratchet 48 engaged by a pawl 49 carried by a disk 50 60 also mounted on the pin 47. Compounded with the disk 50 is a pinion 51, engaged by a toothed segment 52 carried by a pivotally mounted sleeve 53 having an arm 54 provided with a roll 55. A spring 56 tends 65 to hold the toothed segment against a stop

pin 57. The pressure roll 43 is carried by a lever 58 pivoted at 59, and is held toward the feed roll by a spring 60. A suitable detent, not necessary to illustrate, is provided to prevent the feed roll from acting backwardly.

The knife or cutter 46 is guided between blocks 61 (Fig. 3) and is rigidly but removably connected to a clip 62 pivoted at 63 to an arm 64 which is pivoted at 65 to the disk 70 30. Said arm 64 has a side block or projection 66. A spring 67 acts to normally hold the arm and cutter in retracted position against a stop 68.

The parts just described are all located 80 just below, or inside of, a peripheral flange 70 of the disk 30, said flange being slotted to permit the strip material *b* to pass out, and pressure rolls 69 are mounted to bear on said flange or on the blanks passing through. 85 Final pressure rolls may be carried by the shafts 16, 18 as indicated at 71 in Fig. 2.

It is to be understood that to provide for operation on blanks of different widths, not only are the moisteners laterally adjustable 90 on shaft 24, but the disks 30 and the rolls 69 and 71 are also laterally adjustable on their shafts.

The disks 30 are so mounted on the shafts 95 31 that they can be independently adjusted 100 rotatively thereon to accommodate blanks of different lengths. For instance, if the blanks to be corner-reinforced are longer than provided for by the relative setting of the four disks as illustrated in the drawings, then the front pair of disks will be set somewhat advanced, or the rear pair will be set somewhat back, to increase the distance between the operative actions of the strip-feeding and cutting devices. The 105 same adjustment effect can be produced by changing the rotative position of one of the gears 33 on the shaft 31 which carries it.

In operation, each blank passing through the machine has four portions thereof moistened by pads 27, as already explained. Then each blank as it passes between disks 30 and rolls 69, has short sections of reinforcing material *b*, applied to the moistened areas. The feeding of the strips and the 115 cutting off the sections is effected as follows:—The roll 55 passes freely by cam 38 but is actuated as it passes over cam 38. Block 66 passes freely by cam 38 but is actuated by cam 39. When the roll 55 rides 120 over the outer surface of cam 38, the segment 52 is swung, and consequently the feed roll 42 advances the strip the requisite distance, and the front end of the strip passes out through the slot in flange 70. This occurs while the parts carried by disk 30 are moving up toward their uppermost position. Then, just after the projecting end of the strip has been pressed up against the moistened area of the blank, the block 66 rides 125 130

over cam 39, thereby causing the knife 46 to cut the strip. Referring to Fig. 3, it is to be supposed that the action of the knife 46 occurred just before the parts reached 5 the positions shown in said figure.

Having now described my invention in one of its embodiments, what I claim is:—

1. In a machine for affixing reinforcements to sheet material, a rotary member carrying 10 a supply of reinforcing material and having means for severing sections of said material and ejecting them, means for causing the sheet material to travel in a plane tangential to the path of movement of said rotary member, and means for pressing the sheet material and said sections together.

2. A machine of the character described, comprising a plurality of rotary members each having strip-feeding and cutting devices, and means for carrying blanks past 20 said devices in timed relationship to have sections of strip material applied to pre-determined portions of the blanks.

3. A machine of the character described, 25 comprising a plurality of rotary members each having feeding and cutting devices for gummed strips, means for carrying blanks past said devices, means for moistening pre-determined areas of the blanks, and means 30 for automatically insuring accurate spacing of the traveling blanks to cause sections of the strips to be applied to said moistened areas.

4. A machine of the character described, 35 comprising carriers for a succession of blanks, means for moistening pre-determined areas of the blanks, and a plurality of rotary supports for gummed strips, said supports having automatic feeding and cutting devices for the strips.

5. A machine of the character described, 45 comprising four rotary disks, each having strip-feeding and cutting devices, four moistening pads for moistening separate areas of blanks, and means for causing blanks to travel singly in a plane to be first moistened and then receive sections of strip material.

6. A machine of the character described, 50 comprising four rotary members each having strip-feeding and cutting devices, four moistening pads for moistening separate areas of blanks, and means for causing

blanks to travel singly in a plane to be first moistened and then receive sections of strip 55 material, said rotary members being adjustable to vary the timing of their operations relatively to the timing of the operations of the pads according to the distance between the front and rear locations for the 60 strip sections on the blanks.

7. In a machine of the character described, a plurality of rotary disks each having means for supporting and feeding a strip of gummed material and severing 65 means for such strip, an equal number of rotary moisteners, and means for carrying blanks in a plane to be first moistened and then have strip sections applied thereto.

8. In a machine of the character described, 70 a plurality of rotary disks each having a slotted periphery, a knife adjacent the slot, means for feeding a gummed strip past the knife and through the slot, means for causing moistened blanks to travel in a 75 plane tangential to the peripheries of the disks to receive end portions of strip material emerging from the slots of the disks, and means for alternately and intermittently actuating the feeding means and said 80 knife.

9. In a machine of the character described, a plurality of rotary disks each having a slotted periphery, a knife adjacent the slot, means for feeding a gummed strip past 85 the knife and through the slot, means for causing moistened blanks to travel in a plane tangential to the peripheries of the disks to receive end portions of strip material emerging from the slots of the disks, 90 and means for alternately and intermittently actuating the feeding means and said knife, said actuating means comprising a pair of stationary cams.

10. A machine of the character described 95 having four rotary disks relatively positioned at the corners of an imaginary rectangle, each disk carrying strip-feeding and cutting devices, and means for causing blanks to travel past said disks and adjacent thereto to receive strip sections supplied by said disks.

In testimony whereof I have affixed my signature.

MELVIN H. SIDEBOOTHAM.
